UNITED STATES PATENT OFFICE.

JOÃO N. CORREIA, OF NEW YORK, N. Y., ASSIGNOR TO WESTERN ELECTRIC COMPANY,
INCORPORATED, OF NEW YORK, N. Y., A CORPORATION OF NEW YORK.

TELEGRAPH.

Application filed October 23, 1918. Serial No. 259,322.

To all whom it may concern:

Be it known that I, João N. CORREIA, a citizen of Portugal, residing at New York, in the county of New York, State of New York, have invented certain new and useful Improvements in Telegraphs, of which the following is a full, clear, concise and exact description.

This invention relates to telegraph systems and more particularly to systems of cable telegraphy.

The principal object of this invention is to provide an improved method of transmission and organization of apparatus for preventing so-called wandering zero in telegraph line conductors having high electrostatic capacity characteristics.

The present invention is adapted particularly to the transmission of messages according to the Baudot and similar codes made up of permutations and combinations of positive and negative polarities wherein the character of an impulse is controlled by the character of the preceding impulse.

Wherever, in such codes, a plurality of successive impulses of the same polarity would normally occur, the present invention provides that but a single short impulse shall be sent to the line and that following such impulse the line shall be grounded until a reverse impulse occurs.

The invention also provides that the potential of each impulse shall depend upon, and be governed automatically by the duration of the grounding interval immediately preceding and the one immediately succeeding.

This invention is illustrated diagrammatically in the accompanying drawing, in which Fig. 1 serves to illustrate a transmitting system suitable for practicing the features of this invention. In Fig. 2 is illustrated in graphic form the potential and polarity relation of impulse groups of selecting currents as ordinarily applied at the sending end of a line conductor, while in Fig. 3 there is graphically represented the potential and polarity relation of the impulses illustrated in Fig. 2, as actually applied to a line conductor through the operation of the present system.

In describing this system the general principle of its operation will first be considered. Accordingly, this invention provides that a line conductor may be energized during a

momentary period at the beginning of certain impulse intervals only and except for such energizations, the line conductor will be connected to the earth. It is further provided in the transmission of groups of character selecting impulses characterized by permutations of impulses of different current polarities, as in the well known code of Baudot, that following a succession of impulses of like polarity the potential of a next succeeding impulse of opposite polarity will be predetermined by the potential and duration of the previous impulses, and in accordance with such predetermination, current of proper polarity for a succeeding impulse will be automatically selected from a plurality of current supply points having different potentials. A combination of actual potential values which were determined and employed in actual tests have been indicated in the drawing in order to facilitate a more detailed description of the system which will presently be proceeded with.

Under the assumption that a single impulse may be referred to as a short interval, while two or more successive impulses of like polarity may be referred to as a long interval, the general relation of the potentials and polarities, one to another, may be briefly set forth as follows:

When a short interval follows a short interval the current therefor should have a potential of 100 volts; in case a long interval follows a short interval, the current should have a potential of 66 volts; when a short interval follows a long interval, the current should have a potential of 50 volts, and when a long interval follows a long interval the current should have a potential of 40 volts.

The foregoing values were, of course, obtained over a cable having certain electrical time constants or electrical characteristics with respect to the potentials indicated, while the devices at the receiving station at which the impulses were manifested were also of proper electrical time constant relation with respect to the transmitted potentials and the time constant of the cable. Therefore, it will be understood that while these values are true for a given situation, other or different values may be necessary in arriving at the proper potential values for any other cable transmission condition.

In a more detailed description of this sys-

tem, attention will first be directed to Fig. 1 of the drawing, in which reference characters A and B respectively indicate a first and a second quadrant or different telegraphic channels of a multiplex distributor. Corresponding with these distributor quadrants a system of transmitter contact levers 1-10 may be understood as arranged to be controlled by means of a suitably notated or perforated transmitting tape (not shown) as well understood in the art. Oppositely positioned contact stops respectively adjacent these transmitting levers are connected to oppositely poled and grounded direct current sources 21 and 22, respectively, while the transmitting levers connect respectively to segments 11-20 of the distributor. Although this distributor has, for convenience of description, been shown in developed form, it will be understood that it may be of suitable circular construction to provide that three trailer or contactor arms 25, 41 and 61 may travel from left to right over the segments 11-20 and the respectively adjacent collector rings 26, 42 and 62. In operation, the brushes should continue spaced or positioned substantially as shown in the drawing, with respect to each other. Brush arm 25 in passing over a segment which may be energized with positive current from the source 21, establishes this current with the collector ring 26, from which the current may traverse a conductor 27, the windings of two serially connected polar relays 28 and 31 and a resistance unit 34, to earth. As indicated by the conventional plus and minus signs adjacent the armatures of these relays, a positive impulse should cause these armatures to assume the positions in which they are shown in the drawing, while in a converse manner the brush 25 on encountering a segment negatively energized from the source 22 should establish such current through the path already traced, to cause the armatures of the relays 28 and 31 to assume their respective left-hand bias which is opposite to the positions in which they are shown in the drawing. The relays 28 and 31 respectively serve to select different potentials of negative and positive currents as may have been previously selected by two polarized relays 64 and 74. The distributor brush 41 controls the inclusion of either positive or negative currents as may be present on the segments 11-20 through selections effected by the levers 1-10 from the sources 21 and 22, with a collector ring 42 which is connected by means of a conductor 43 in branch relation through the windings of two polar relays 44 and 47. In series with the relay 44 there is provided a resistance unit 50 and a condenser 51, while a resistance unit 52 and a condenser 53 are similarly connected

in series with the relay 47. The presence of the condensers 51 and 53 in the operating circuit of these relays, render the currents supplied by the brush 41 of momentary effect only, and since these relays are biased as indicated, to normally retain their armatures in the positions in which they are shown in the drawing, an impulse of positive current will cause the relay 44 to momentarily separate its contacts 45 and to close its contacts 46, while the same impulse will not affect the relay 47, except to additionally stress its armature in maintaining its contacts 48 closed. In a converse manner an impulse of negative current supplied through the brush 41 would cause the relay 47 to momentarily separate its contacts 48 and to close its contacts 49, while the armature of the relay 44 would continue on its normal bias in establishing its contacts 45. It will therefore be clear that a line conductor L connected to the armature of the relay 47 is normally connected by way of the contacts 48 of the relay 47 and the contacts 45 of the relay 44, to earth. Since the contacts 49 of the relay 47 control a connection extending to the armature of the selectively controlled switching relay 28, it will be obvious that during any instant the relay 47 may be operated its contacts 49 will connect the line conductor L through either the contacts 29 or the contacts 30 of the relay 28 to receive negative current of such potential as may have been selected through either one or another of the contacts 65, 66 or 67, and 68 of the latter relay. In a corresponding but inverse manner, momentary responses of the relay 44 to impulses of positive current will connect the line by way of the contacts 48 of the relay 47 and the contacts 46 of the relay 44 to the armature of the positive-current selecting relay 31, whence positive current having a potential as previously selected by the relay 74, may become effective with the line L.

The brush 61 in traveling through its path, successively joins the segments 11-20 with a collector ring 62 and in accordance with prepared energizations of these segments by way of the transmitting contacts 1-10 such currents may traverse a conductor 63, the serially connected windings of the polar relays 64 and 74 and a resistance 70 to earth. For convenience of illustration, each of the latter relays has been provided with two armatures which are similarly acted upon by any current through the associated relay windings, and as indicated by the plus and minus signs adjacent the armatures of these relays, a positive impulse should establish biasing to close the contacts 65 and 67 of the relay 64 and to close the contacts 75 and 77 of the relay 74. In a similar but converse manner, the effect of a negative impulse of current applied to

these relays through the brush 61 should cause the relay 64 to close its contacts 66 and 68, while the relay 74 will close its contacts 76 and 78. It will be mentioned that a condenser 71 connected in parallel with the resistance unit 70 and a condenser 35, similarly connected in parallel with the resistance unit 34 of the operating circuit of the relays 28 and 31, are for the purpose of providing capacity which may be adjusted in connection with the respectively associated relay circuits in such a manner that any desired effects with respect to the time constant relation of the relay circuits may be secured.

In order to illustrate an actual application of different potentials to the line conductor L in accordance with this invention, a transmission example will now be assumed and the various operations or steps necessary in disposing of such a combination of impulses will be traced and considered in detail. Therefore, as illustrated by the polarity line 80 in Fig. 2 of the drawing, let it be assumed that for the channel A a combination of 5 impulses will be prepared in the order of a first and a second positive impulse, a third negative impulse, a fourth positive impulse, and a fifth negative impulse, while for the second channel B a combination comprising a first negative impulse, a second, third, and fourth positive impulse, and a fifth negative impulse will be prepared. For such impulse combinations the transmitter levers 1, 2, 4, 6 and 10 will stand in their respective forward positions, which are opposite to the positions in which they are shown in the drawing, while the levers 3, 5, 7, 8 and 9 will stand in their respective normal positions which is the position in which they are shown in the drawing. Assuming now that the relays 28, 31, 64 and 74 will be positioned as shown in the drawing, due to the brushes 25 and 61 having respectively encountered positively poled segments in other distributor quadrants or channels not shown. The brush 25 on arriving over the segment 11 will establish positive current from the source 21 over the circuit already traced, to retain the relays 28 and 31 in the positions in which they are shown, and since the transmitter contact 2 is also connected with the source of positive current at this time, these polar relays will continue on the same bias during the time the brush 25 is also passing over the segment 12. On arriving over the segment 11, the brush 41 will establish positive current over the circuits already traced to momentarily operate the relay 44. This establishes a circuit which may be traced from the line conductor L through the contacts 48 of the relay 47, the contacts 46 of the relay 44, the contacts 32 of the relay 31, and the contacts 77 of the

relay 74 to a positively poled and grounded source of current having a potential of 66 volts, as indicated in the drawing. Since the impulse combinations assumed for the transmitter contacts 1—10 corresponds with the shaded line 80 in Fig. 2 of the drawing, reference may be had to Fig. 3 of the drawing wherein the shaded line intervals represent in a theoretical form the actual moments during which the line L may be energized under the transmission of the prepared impulse combinations. The lines paralleling the zero line O (Fig. 3) are respectively designated as 100-V, 66-V, etc. to correspond with the various potentials of the currents employed in illustrating this system. Therefore the first impulse of positive current just traced to the line L will correspond with the first or left hand impulse further identified as of positive polarity and having a potential of 66 volts. At the time this impulse becomes effective with the line L, the brush 25 will be passing over the positively energized segment 12 and accordingly relays 28 and 31 will continue biased as shown. On the brushes advancing to the next respective segments negative current from the source 22 to the segment 13 may traverse the brush 25 to negatively bias the switching relays 28 and 31, while the brush 41 now over the positively energized segment 12 will be non-effective to again operate the relay 44 for the reason that the condenser 51 retains the positive charge which continued during the time the brush 41 was traversing the positively energized segment 11. In substitution of a current impulse the line conductor L will therefore continue grounded through the contacts of the relays 44 and 47 during the interval corresponding with the second impulse of the assumed combination. Arriving at the next position, the brushes 25, 41 and 61 will be over the segments 14, 13 and 11, respectively. The brush 25 now joins the positively energized segment 14 to correspondingly bias the relays 28 and 31, while the brush 61 in connecting the positively energized segment 11 to the relays 64 and 74 does not affect these relays which now stand biased to their positive positions as already described. At this time the brush 41 may therefore join the negatively poled segment 13 to momentarily operate the relay 47, thereby completing a circuit which may be traced from the line conductor L by way of the contacts 49 of the relay 47, the contacts 29 of the relay 28, and the contacts 67 of the relay 64 to a source of negative current having a potential of 50 volts, as indicated in the drawing. On the brushes advancing to the next segments 15, 14 and 12, respectively, the brush 25 causes the relays 28 and 31 to be negatively biased while the relay 44 will be op-

erated to momentarily connect the line L by way of the contacts 48 of the relay 47 over the contacts 46 of the relay 44, thence through the contacts 33 of the relay 31 and the contacts 75 of the relay 74 to a source of positively poled current indicated as having a potential of 100 volts. The brush 61 at this time applies positive current from the segment 12 through the relays 64 and 74 and these relays will therefore remain on their present positive bias. On arriving over the segment 16 the brush 25 again encounters negative current and the relays 28 and 31 will accordingly continue on their present negative bias, while the brush 61 now establishes negative current from the segment 13 to oppositely or correspondingly bias the relays 64 and 74. The brush 41 at this instant connects negative current from the segment 15 to momentarily operate the relay 47 to close its contacts 49, thereby switching the line conductor L to a circuit which extends through the contacts 30 of the relay 28 and the contacts 66 of the relay 64 to a source of negative current having a potential of 66 volts, as indicated. This impulse being the fifth or last impulse of the selecting combination for the first channel A the transmission of the character selecting combination for this channel will be completed thereby. On the brushes arriving over the segments 17, 16 and 14, respectively, current from the positively charged segment 17, over the brush 25 will bias the relays 28 and 31 to the positions shown in the drawing, positive current from the segment 14 over the brush 61 will correspondingly bias the relays 64 and 74 while negative current from the segment 16 over the brush 41 will be non-effective to operate the relay 47 since the condenser 53 stands charged with negative current received during the time the brush 61 was traversing the negatively charged segment 15, therefore no energization of the line conductor takes place during this first impulse interval of the impulse combination for the second channel but instead, the line conductor continues grounded, as already traced. When the brushes respectively arrive over the segments 18, 17 and 15, positive current from the segment 18 will act over the brush 25 to retain the relays 28 and 31 on their present positive bias. Negative current from the segment 15 will be established over the brush 61 to negatively bias the relays 64 and 74 while positive current from the segment 17 may act over the brush 41 to energize the relay 44, thereby connecting the line conductor L through the contacts of the relay 47 by way of the contacts 46 of the relay 44, the contacts 32 of the relay 31 and the contacts 78 of the relay 74 to a source of positively poled current indicated as having a potential of 40 volts. For the next or third

impulse interval in this channel, the brushes will be respectively over the segments 19, 18 and 16. The brush 25 will accordingly establish the positively energized segment 19 to positively bias the relays 28 and 31, 70 while the brush 61 will apply negative current from the segment 16 which will not affect the relays 64 and 74 on their present negative bias. The brush 41 now establishes positive current from the segment 18 with 75 the relay 44. This relay will not be affected by this current, however, since its associated condenser 51 is already charged with current of this sign as previously received while the brush 41 was over the segment 17. The line conductor L will therefore continue grounded, as already described, during this third impulse interval. For the fourth impulse the brushes will be respectively over the segments 20, 19 and 17. 85 Negative currents from the segment 20 over the brush 25 will correspondingly bias the relays 28 and 31, while positive current from the segment 17 over the brush 61 will correspondingly bias the relays 64 and 74. The brush 41 now establishes positive current from the segment 19 which encounters a positive change in the condenser 50 due to the current from the segments 17, 18 and 19 similar to the effects already described. 90 Therefore the cable continues grounded during the period corresponding with the fourth impulse interval. In transmitting the fifth or last impulse for the present combination of the second channel, the brush 25 will have 100 advanced to the first segment in a third channel (not shown) and, for convenience of illustration in carrying out the operations for the present combination, let it be assumed that such segment of the third channel would be energized with positive current to act over the brush 25 in positively biasing the relays 28 and 31. It will be pointed out that the combinations of impulses assumed for the two channels happen 105 to be of such relation that in case the distributor consisted of only the two channels shown and that the segments 20 and 11 would be adjacent in forming a segmented ring the brush 25 would be over the segment 11 at this moment and assuming for purpose of description that the "set up" of the combination considered is still present in the first channel this brush would accordingly receive the necessary positive current 110 from the segment 11. At this time positive current from the segment 18 traverses the brush 61 and retains relays 64 and 74 on their present positive bias. Negative current from the segment 20 may now traverse 115 the brush 41 to energize the relay 47, thereby completing a circuit from the line conductor L which may be further traced through the contacts 49 of the relay 47, the contacts 29 of the relay 28 and the contacts 67 of the 120

125

130

relay 64 to the source of negatively poled current having a potential of 50 volts. By inspection of Figs. 2 and 3 of the drawing it will be seen that the assumed impulse 5 combinations, as illustrated in Fig. 2, would have required 10 impulses of current but in the actual transmission operations, wherein grounding of the line conductor was substituted for successively recurring impulses 10 of the same polarity only six impulses of current were actually imparted to the line conductor, the line continuing grounded during all periods intermediate such actual momentary inclusions of current therewith. 15 It will also be clear that the condensers 51 and 53, as connected serially in the operating circuits of the relays 44 and 47, respectively, serve to render the current effects with these relays as established by the brush 44 only 20 momentarily effective to move the armatures to their forward positions and since the operating circuits of these relays are connected in parallel, one with the other with respect to the energizing lead 43, the condensers 51 and 53 will always receive and 25 retain current charges of like polarity and, therefore, these condensers cannot discharge accumulatively one condenser with the other. It will also be understood that the speed of the distributor may be sufficiently 30 high with respect to the spacing of the segments to prevent any appreciable leaking from the condensers during the time the brushes 25 and 41 are passing from one segment to another. This feature, relative to 35 the connective relation of the condensers, prevents operation of either one of the relays 44 and 47 during impulse intervals corresponding with successive repetitions of 40 impulses of current of like polarity.

What is claimed is:

1. The method of telegraphy which consists in alternately energizing and grounding a line conductor and in varying the value of the potential strength of said line energizations by gradations in a predetermined manner.
2. The method of telegraphy which consists in alternately energizing and grounding a line conductor and in varying the potential strength of said line energizations in a predetermined manner with respect to the duration of the groundings of said line.
3. In a telegraph system, a line circuit, means for alternately energizing and grounding said line, and means for varying the value of the potential strength by a plurality of gradations in a predetermined manner.
4. In a telegraph system, a line conductor, means for alternately energizing and grounding said line, and means for varying

the potential strength of said line energization in accordance with the duration of a preceding ground interval.

65

5. A telegraph system in combination with a signaling conductor, means for preparing predetermined combinations of current impulses, means for impressing said impulses on said signaling conductor, and further means controlled jointly by the polarity of the impulse immediately preceding and the second impulse succeeding each impulse for determining the potential strength of such impulse.

75

6. In a telegraph system, a line conductor, a plurality of sources of current having different potential strength, means for preparing predetermined combinations of current impulses, electroresponsive means controlled by said impulses for alternately energizing and grounding said line, and means selectively operated for including with said line conductor one of said sources of current.

80

7. In a telegraph system, tape controlled transmitting contacts, means for preparing permutations of current polarities at said contacts, a first pair of oppositely responding polar relays, distributor means for rendering said contacts effective in controlling said relays, a positive and a negative current source each having several selectively different potentials, a second pair of relays controlled by said distributor for selecting predetermined potentials and polarities from said sources, a third pair of relays controlled by said distributor for applying potentials selected by said second pair of relays to be controlled by said first pair of relays, and means controlled by said first pair of relays for alternately energizing and grounding said line circuit.

90

8. In a telegraph system, a line, means for preparing predetermined combinations of current impulses, a distributor, a plurality of sources of current of different polarities and strengths, a plurality of relays having their armatures normally connected with said line and controlling the energization thereof, means associated with said relays for effecting the grounding of said line in substitution of successively recurring impulses of the same polarity, and means controlled by said distributor for impressing on said line a current impulse following a ground interval the potential strength of which is dependent upon the duration of such ground interval.

95

10. In witness whereof, I hereunto subscribe my name this 18th day of October A. D., 1918.
